FIXTURE MEANS FOR CURTAIN AND
DRAPEY HANGERS

Anthony P. Veschio, Monessen, Pa.

Application November 1, 1949, Serial No. 124,862

7 Claims. (Cl. 211—105.3)

1

The present invention relates to certain new and useful improvements in curtain and drapery rods, special brackets or fixtures, and the like, attachable to a wall, window frame or the like for hanging and maintaining curtains and drapes properly and effectively in place.

Manifestly, I am conversant with the state of the prior art to the extent that I realize that countless styles and forms of extensible rods, hangers, cranes, fixtures, brackets and the like, have been and are being used. Notwithstanding prior art developments, I have evolved and produced structural means which, by contrast with known hardware and accessories in the same field of invention possesses refinements and improvements of an appreciable and worthy degree.

In carrying out the principles of the inventive concept, I provide simple and economical brackets and special fixtures which are attachable to conventional-type window construction, said brackets and fixtures being of such construction that they serve to support coacting ends of conventional-type tubular curtain and drapery rods, special ornamental hangers for festoon drapes, and for crane-type extensible arms.

Another object of the invention is to provide improved rods whose laterally directed end portions are equipped with especially designed inserts or adapters which facilitate their coaction with complementary features of accommodation provided therefor on the relatively stationary brackets for said adapters.

More particularly, the improved window frame bracket, in each instance, is characterized by plates or equivalent elements, which constitute attaching means and are rigidly connectible, usually with the window frame, having a depending hook in which an end-fitting or adapter, carried by the curtain or drapery suspension means, is adapted to be removably saddled and which also includes an overlying detent which is spaced from but complementary to said hook and is co-operable with said adapter.

Specifically, in carrying out an embodiment of the novel means adopted, I provide an anchoring bracket for suspending the lateral terminal or adapter of a U-shaped curtain or drapery hanging rod comprising a horizontally disposable attaching plate for attachment to a window frame, said plate having a depending hook and a horizontal lug, the latter being a detent and spaced from the hook and occupying a plane above the bill of the hook, there being a curtain rod having a lateral adapter, the terminal of which is

2

rounded, pointed, and provided with a keeper notch, the rounded terminal or tip serving to pilot the adapter "home" and said adapter being saddled in the crotch of the hook, the pointed end underlying said detent and the latter being removably held in said keeper notch.

In reducing to practice my overall ideas, I provide first, a window frame or anchoring bracket with pairs of special saddling hooks and overlying detents; secondly, a notch equipped pointed adapter, usually telescoped and frictionally fitted into the lateral tubular end portion of a regular U-type curtain or drapery rod; thirdly, V-shaped or equivalent ornamental fixtures or accessories which are best used for suspending drapes, festoon style, and, finally, I also have special adapters to accommodate "crane-type" drapery suspending arms.

Other objects and advantages of the invention will become more readily apparent from the following description and the accompanying sheet of illustrative drawings.

Figure 1 is a perspective view, depicting a fragmentary portion of a window frame and showing the improved curtain and drapery rods and also the dual-type brackets for attaching said rods.

Figure 2 is a perspective view of an "exploded type" on a larger scale, showing one of the window brackets and also showing the special construction of one of the adapters.

Figure 3 is a top plan view of the bracket seen in Figure 2.

Figure 4 is an edge elevation of said bracket.

Figure 5 is a fragmentary perspective view, like Figure 1, but showing a modification, that is, a V-shaped fixture for hanging drapes festoon-style.

Figure 6, like Figure 2, is a perspective view, suitably enlarged and "exploded," showing more clearly the bracket and fixture means of Figure 5.

Figure 7 is another fragmentary perspective view, based on Figures 1 and 5, but showing how an extensible "crane-type" arm is attached to the special adapter provided therefor.

The relatively stationary brackets are the same at both ends of the window frame, are the same in all figures of the drawings and are denoted by the numerals 7 throughout the figures. In Figure 1 the curtain rod is denoted by the numeral 8 and the drapery rod by the numeral 9. Except for size and inner and outer positions, these rods are basically alike. It will be seen, in all figures, that the anchoring bracket 7 comprises an upper rectangular attaching plate 10 and an underlying slightly shorter rectangular plate 11,

the two plates having openings 12 for passage of fastening screws. The plate 11 is provided at the left-hand end with a suspension hook 13, the crotch or seat of which is denoted by the numeral 14 and a bill by the numeral 14a. On the same end of the plate 11 and spaced from the hook 13 is an outstanding lug 15 which is down-bent and provided with a hooked detent 15a. The projecting end-portion of the top plate 10 also has a depending hook 16 with a crotch portion 17 defining a bill 17a. This plate also has a lug 18, slightly longer than the first-named lug and superimposed on the latter and lug 18 has a depending hook 19 which constitutes a second detent. The lug 15 lines up with the crotch of hook 14 and the lug 18 lines up with the crotch 17 of hook 16. These hooks 13 and 16 are obviously for selective reception of the laterally directed end portions of the curtain and drapery rods 8 and 9. In Figure 2, I show one of the laterally directed terminals of rod 9 and this constitutes an adapter which is denoted by the numeral 20 and has retentive corrugations 20a and a reinforcing rib 21. The upper surface of said rib is provided, just short of the terminal or tip, with a keeper notch 22. In addition and at the point 23, the lower edge of said adapter 20 is longitudinally curved and merges into the tip or terminal as at 24. This tip is adapted, therefore, to provide a piloting nose 24 and keeper seat 22 for said adapter 20. It is obvious that, under this arrangement, the pilot 24 is easily fed and guided into the crotch 17 where it is allowed to saddle and fulcrum, and then by lining up the lug 18 with the keeper notch 22, the adapter 20, by bridging both parts, the hook 16 and lug 18, is detachably lodged and securely, but removably anchored in place.

The detailed description preceding is primarily directed to the form of the invention in Figures 1 to 4, inclusive. Briefly summarized, said subject matter is directed to the special two-way brackets 7 and the adapters 20, singly or collectively.

Reference is had now to the modification depicted in Figures 5 and 6. Since the window frame bracket is exactly the same, the same reference numerals and lead lines are used to "tie in" with Figures 1 to 4. However, the V-shaped drapery fixture is different and is denoted, as a unit, by the numeral 26.

Fixture 26 is characterized by a single unit embodying vertical and horizontal portions. The vertical portion, as a general rule, will be either V-shaped or U-shaped in construction and will therefore include upwardly and outwardly diverging members 27 and 28 forming a suitable crotch 29 in which the vertical panel portions of a window drape may be lodged and suspended, as shown in dotted lines in Figure 5. In actual practice, the members 27 and 28 may be stamped out or otherwise made to delineate flowers, bird wings and so on and so forth. The horizontal portion, which is the attachment and anchoring means for the overall fixture, is denoted by the numeral 30, and this is also an "adapter" and corresponds to the aforementioned adapter 20. For this reason, the tip or terminal is curved, as at 31, to provide a suitable piloting nose to be fed into the crotch portions 14 or 17 of the hooks 13 and 16. The upper straight edge has a clearance cut-out, as at 32, and is adapted to rest underneath of the chosen detent 15 or 18, as the case may be. Instead of having the keeper notch in the top edge of the adapter, as shown in Figure 2, said notch

33 is in the lower edge. Here, it is properly situated to nest itself nicely in the crotch portion of the hook, say, for instance, the hook 16 as shown in Figure 5 of the drawings.

5 It will be clear that the brackets 7 are the same throughout, that the curtain or drapery hanger may be either the U-shaped rod-type shown in Figure 1, or the V-shaped type shown in Figures 5 and 6. In both adaptations, the adapters, 20 and 30, respectively, have common structural characteristics and are correspondingly made to fit the brackets 7. Both adapters have keeper notches and pilot means. The principal difference is that the adapter 20 has the notch 22 in the top edge while the adapter 30 has the keeper notch 33 in its lower edge. The claims are therefore drawn in generic and specific terminology to comprehend these common characteristics.

20 Taking up now the embodiment or modification of Figure 7, the "crane-type" extension arm is denoted at 34 and the inward section 35 of same has a downturned end or journal 36 hinged in a socket member 37 formed integrally on one end of the adapter 38. Here again the adapter is like the one shown in Figure 6 and has a clearance and angling recess 39 in the upper edge and an adapter notch 40 in the lower edge and a pilot-nose 41. At this stage, I would add that the adapters in Figures 6 and 7 both have a stop shoulder. The latter is denoted at 33a in Figure 6 and 40a in Figure 7 and said shoulders nicely check the adapters as they are sent "home," whereby to avoid undesirable forcing and hanging of the nose-ports with consequent damage to the wall surface or wall paper (not shown), as the case may be.

The present application is a continuation-in-part of my copending application, Serial No. 793,872 filed December 26, 1947, allowed April 22, 1949 and which became abandoned on Nov. 3, 1949.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

45 Minor changes in shape, size, materials and rearrangement of parts may be resorted to in actual practice so long as no departure is made from the invention as claimed.

Having described the invention, what is claimed as new is:

53 1. In combination, a bracket comprising a horizontally disposable attaching plate for fixed attachment to a part of a window construction, said plate having a depending hook with a crotch and bill and a horizontal lug, the latter being horizontally spaced from the hook and occupying a plane above the bill of said hook, and a drapery hanging means provided with an adapter, the terminal of which is rounded, pointed and provided with a keeper notch, the rounded and pointed portions serving to pilot said adapter so that latter may be saddled in the crotch of the hook with the pointed terminal underlying said lug.

plate being provided with a substantially duplicate depending hook and a substantially duplicate lug and hooked detent, said hook and lug of each plate being horizontally spaced from one another in such relation as to accommodate adapters on curtain and drapery supports.

3. As a new article of manufacture, a substantially U-shaped curtain or drapery rod embodying a body portion and lateral adapters, each adapter being the same and including a 10 curved tip constituting a pilot, a reinforcing rib on the upper edge, said rib having a notch and said notch constituting a keeper seat adapted to coact with a part of a window bracket.

4. In combination, a bracket adapted to be 15 fixedly attached to a window frame and comprising plate means having an outstanding lug with a hooked detent at one end, having a depending hook with a crotch portion at the same end, said detent being substantially in the same plane as said plate means, the crotch portion of said hook being on a plane below said plate means but lined up for coaction with said leg and detent, and a drapery hanger embodying an adapter having a lower edge portion saddled in the crotch of the hook and an upper edge portion underlying said lug, said upper edge portion having a keeper notch and said lug fitting removably into said keeper notch.

5. In combination, a bracket adapted to be 20 fixedly mounted on a window frame, said bracket embodying horizontally disposable plate means, the latter being provided at one end with a hook depending at right angles from and provided with crotch and bill portions situated on a plane slightly below the plane of the plate means, the latter also having an outstanding lug, said lug having a detent, said lug being laterally spaced from and in alignment with 25 said crotch and in a plane with said plate means, said crotch and in a plane with said plate means, an adapter interposed between and bridging the

hook and lug, said adapter being removably seated in said crotch, the upper edge of the adapter underlying said lug, the lower edge of the adapter having a keeper notch releasably engaged with said hook.

6. The structure specified in claim 1, wherein said drapery hanging means comprises a vertically disposed V-shaped member adapted to receive a window drape in festoon style.

7. In combination, a bracket comprising a horizontal plate adapted to be fixedly mounted on a part of a window construction, said plate having a depending hook and a horizontal lug, said lug being horizontally spaced from said hook and occupying a plane above the free end portion of said hook, an adapter limb having a curvate piloting nose at one end, having a vertically disposed socket member at its opposite end and provided intermediate its ends with a shouldered recess, the latter being situated in an edge portion of the limb, and a crane-type arm having a lateral portion mounted for oscillation in said socket member.

ANTHONY P. VESCHIO.
